UNITED STATES PATENT OFFICE.

MICHAEL JARMIE, OF EAST HAVEN, CONNECTICUT.

SPRING-LUBRICATOR.

1,342,172.

Specification of Letters Patent.

Patented June 1, 1920.

Application filed November 19, 1919. Serial No. 339,221.

To all whom it may concern:

Be it known that I, MICHAEL JARMIE, a citizen of the United States, residing at East Haven, in the county of New Haven 5 and State of Connecticut, have invented certain new and useful Improvements in Spring-Lubricators, of which the following is a specification, reference being had therein to the accompanying drawings.

10 My invention relates to a new and useful spring lubricator, having more particular reference to mechanism of this type that is applied to a laminated spring for the purpose of providing a continuous supply of 15 lubricant to the friction points between the several leaves of the spring.

It is the object of this invention, among other things, to provide a simple, inexpensive and easily applied device that will provide 20 for the efficient lubrication of the leaves of the spring and so designed and arranged that the entire pressure required to hold the device in place will bear upon the lubricating felt or wick only at the edges 25 thereof.

To these, and other ends, my invention consists in the spring lubricator, having certain details of construction and combinations of parts, as will be hereinafter 30 scribed and more particularly pointed out in the claims.

Referring to the drawings, in which like numerals of reference designate like parts in the several figures;

35 Figure 1 is an elevation of my new and improved device as applied to a laminated spring;

Fig. 2 is an end elevation thereof, partly in section and these upon line 2-2 of 40 Fig. 1;

Fig. 3 is a fragmentary sectional plan view of one of the plates, taken generally upon line 3-3 of Fig. 2.

Devices of this character have been here- 45 tofore constructed so that the entire felt or wick in contact with the leaves of the spring is under pressure applied uniformly by the holding plate or cover. The result of this is that the felt or wick in time be- 50 comes so packed and hardened by this pressure as to be of little or no value as a trans- 55 mitting element for the lubricant and therefore requires frequent replacing. To offset this difficulty devices have been so designed that the plates overlap the top and bottom of the spring so as to relieve somewhat the

weight of the device and the pressure of holding it. With this latter structure it is obvious that pressure must be applied to the felt or wick as before and that while the 60 overlapping portion of the plates at the top and bottom of the spring assists somewhat in supporting the device it is objectionable because two additional friction surfaces are added by each plate, and no provision is 65 made for lubricating them.

In my device I have overcome these and other objections to the devices in the prior art. The parts of my device are so designed and constructed that pressure is applied to 70 the wick or felt at only a limited portion of its surface and around its outer edges, the wick or felt therebetween not being subject to pressure and constructed of material of such weight and texture as to provide a lu- 75 bricant transmitter of maximum efficiency.

Referring to the drawings, the numeral 10 designates one of the side or cover plates which are preferably constructed of a single 80 piece of metal with a concaved central portion 11 terminating on two sides in the flanges 12, from which project the ears 13, which are provided with openings 14 for the reception of the bolts 15 having the nuts 16 threaded thereon. Between the flanges 85 12 on the side plates 10 the sides 17 of the central portion 11 terminate on a plane with the inner face of the flanges and ears 13.

Threaded into each of the plates 10 is an oil or grease cup 19 of standard construc- 90 tion, which provides a reservoir for the lu- bricant which enters the chamber in the in- terior of the central portion 11. Within 95 said chamber is a pad 18 of light woven felt or similar material so shaped as to be slightly thicker in the center between its ends and narrowing toward its outer edges, which is of uniform thickness as shown at 20 to extend under the flanges 12 and the bottom edges of the sides 17. In assem- 100

bling, the pad 18 is between the plate and springs 21, and as that portion thereof in the chamber in the central portion 11 is of slightly less thickness than the depth of the chamber, pressure is only applied to the pad 105 at its outer edges under the flange 12 and the sides 17. By this construction, the hold- 110 ing pressure is taken entirely upon the outer edges of the pad and the intermediate portion performs its function solely as a lubri- cant conveyer and operates in a well known manner, the lubricant being transmitted

thereto through the oil cups 19. The more compact portion of the pad now being its outer edges, leakage of lubricant is prevented, a common and serious fault in the devices of the prior art.

There are minor changes and alterations that can be made within my invention; aside from those herein suggested, and I would therefore have it understood that I do not 10 limit myself to the exact construction herein shown and described, but claim all that falls fairly within the spirit and scope of my invention.

Having described my invention, what I 15 claim as new and desire to secure by Letters Patent, is:

1. In a device of the character described, the combination with companion plates; of means for securing the same together upon 20 opposite sides of a laminated spring; and a pad of felt or similar material for each of said plates lying between the spring and plates, the pressure contact of the plate upon said pads being applied solely around 25 the outer edges thereof.

2. In a device of the character described,

the combination with companion plates, each of said plates having a recessed inner face; of means for securing the same together upon opposite sides of a laminated 30 spring; and a pad of felt or similar material for each of said plates lying between the spring and plate, the pressure contact of the plate upon said pads being applied solely around the outer edges thereof by 35 that portion of the inner face of said plate surrounding said recess.

3. In a device of the character described, the combination with companion plates; of means for securing the same together upon 40 opposite sides of a laminated spring; a pad of felt or similar material for each of said plates lying between the spring and plate and held so that the outer edges thereof are under pressure and the intermediate portion 45 free from pressure; and means for supplying a lubricant to that portion of said pad that is free from pressure.

In testimony whereof, I have hereunto affixed my signature.

MICHAEL JARMIE.
